UNITED STATES PATENT OFFICE.

WALLACE PFAU ANDRICK, OF JAMAICA, NEW YORK, ASSIGNOR TO GENERAL ACOUSTIC COMPANY, OF JAMAICA, NEW YORK, A CORPORATION OF NEW YORK.

DICTOGRAPH INTERCOMMUNICATING TELEPHONE SYSTEM.

1,160,125.

Specification of Letters Patent. Patented Nov. 16, 1915.

Application filed October 10, 1913. Serial No. 794,501.

To all whom it may concern:

Be it known that I, WALLACE PFAU ANDRICK, citizen of the United States, and resident of Jamaica, in the county of Queens 5 and State of New York, have invented certain new and useful Improvements in Dictograph Interscommunicating Telephone Systems, of which the following is a specification.

This invention relates to a telephone system involving one or more stations, adapted to be made part of an intercommunicating system, and also one or more additional stations, hereinafter termed "master stations," 15 which are distinguished by the fact that they have sensitive transmitters and loud speaking receivers, and a private or individual line connection to every other station with which they may be connected. This sort of system is adapted to factories and business 20 purposes, where there are a few administrative heads, and many subordinate departments. The subordinate departments are satisfied by the ordinary intercommunicating station, without sensitive and loud speaking instruments, and in many cases without 25 secrecy, but the administrative heads require a better service, afforded by the sensitive and loud speaking instruments, and by the feature of secrecy in the communications. In 30 the matter of signaling, also, the administrative heads should have the best possible service, and it is desirable that such administrative heads be able to call another station 35 without bothering with a code. By a code is meant such a practice as having one station call with two rings, and another with three rings, so that the called station may know who to answer. This may occasion 40 some inconvenience which it is desirable to avoid. Moreover, it is desirable to have the administrative head or master station able 45 to call any other station, particularly the subordinate stations, even if the latter are talking among themselves. Otherwise, the 50 administrative head might be obliged to wait for the termination of some relatively unimportant conversation. It is, of course, also evident that the master stations should not 55 be called by any accidental circumstances, for example, as when one sub-station calls another. In systems of this class combinations of circuits sometimes occur which are apt in cases to send signaling currents

through paths different from the normal 55 ones intended, and means must be provided to avoid any accidental or unintentional signaling of any station in this way. Also accidental talking circuits must be vigorously guarded against, on account of secrecy, as 60 there must be no improper electrical connections during talking.

A further cause of non-secrecy in telephone systems arises from what is known as "crosstalk" which is the result of induction 65 between circuits which are not actually physically connected with one another. This may happen also by reason of the inability of retardation coils to prevent telephonic currents being transmitted where the 70 sensitive instruments of a master station are involved. Accordingly these effects must be guarded against in addition to the effects of the accidental direct branch circuits or 75 connections. Moreover, the connection of 80 each master station with the stations of the intercommunicating system should not interfere with any result or practice already existing in simple combinations of master or other stations, such for example as disclosed in U. S. Patents No. 843,186 and 927,230. It is the object of the present invention to provide an improved telephone 85 system satisfying all the foregoing requirements.

In the drawings, Figure 1 is a diagrammatic view showing two master stations and three stations of an intercommunicating system, two of the intercommunicating stations being adapted for communication to the 90 master stations. Fig. 2 is a diagrammatic view showing a single master station and three intercommunicating stations, two of which are adapted for communication to the master station, this modification however 95 differing from that of Fig. 1 in the fact that code signaling will be used where more than one master station is connected.

Referring to Fig. 1, A¹ and A² denote master stations and X, Y and Z sub-stations 100 or intercommunicating stations.

The master stations have a plurality of keys 1, 2 and 3, respectively, controlling individual line connections to the other stations and to each other. Key 1 controls a 105 line connection to the other master station, while keys 2 and 3 control connections to the sub-stations X and Y. In addition to

these keys the master stations have, in the best practical construction, visual signals 4 which also act as relays, and an audible signal 5. The master stations further have 5 ringing keys 6, ordinarily actuated by the same finger piece which makes the talking connection. It is of course evident that separate controlling levers, or jacks may be used. The master stations further have a 10 sensitive transmitter 7 and a loud speaking receiver 8, and also an ordinary receiver 9 may be provided. There is also a talking battery 10 and a ringing battery 11, although the latter may be dispensed with if 15 desired, a suitable tap being provided to the ringing battery of the intercommunicating lines.

24 is a switch hook controlling the receiver 9.

20 The intercommunicating stations each have a sensitive transmitter 13, a receiver 14, retardation coils 15 and an audible signal 16 which may be generally referred to as the station instruments. There are also 25 keys 17 and 17', or known equivalents therefore, governing the connections to the other intercommunicating stations and the master station. The stations furthermore have visual signals 18, in the practical construction 30 illustrated, in Fig. 1 corresponding in number at each station to the number of master stations of the system with which that station is connected. There is also a switch hook 12 and a ringing key 20 at each substation.

In the best constructions embodying the invention each sub-station has a relay 21, the purpose of which is to connect the audible signal across the battery when a master 40 station calls a sub-station.

The various circuits can best be described by tracing them for the various conditions which occur in practice, for example:—

1. When one sub-station calls another.
- 45 2. When, the second station answering, telephonic communication takes place.
3. When one master station calls another.
4. When, the master station answering, conversation takes place.
- 50 5. When a master station calls, a sub-station.
6. When, the sub-station answering, conversation takes place.
7. When a sub-station calls a master station.
- 55 8. When, the master station answering, the conversation takes place. This is the same as No. 6.
9. When a master station calls a busy substation.
- 60 10. When a sub-station calls a busy master-station.

The foregoing are the main ordinary circuits established and used in the system, corresponding to what may be termed normal

traffic conditions. In addition to these circuits, many connections exist in the shape of branches from the circuits already traced, through which additional or branch circuits might occur were it not for the fact that in every such case interruptions have been provided which prevent any harmful effects on the working of the system.

Taking up now the various electrical circuits, in the order of the numbered paragraphs just above given, the circuits when one sub-station calls another, for example when X calls Y are as follows:—Negative ringing battery R', wire l¹, wire l², wire l³, contacts of ringing key 20, wire l⁴, wire l⁵, contacts of key 17, wire l⁶, wire l⁷, wire l⁸, switch hook 12, signal 16, wire l⁹, wire l¹⁰, back to positive battery R'. As a result of this call station Y removes receiver from the hook and telephonic circuits are established as follows:—Battery T', wire m¹, wire m², retardation coil 15, wire m³, wire m⁴, contacts of key 17', wire m⁵, contacts of other key 17', wire m⁶, transmitter 13, receiver 14, wire m⁷, contacts of key 17', wire m⁸, through a contact of the other master key 17', wire m⁹, switch hook 12, wire m¹⁰, retardation coil 15, wire m¹¹, back to battery T'. This circuit serves to bridge the telephone transmitter, and the telephone receiver at station X across the terminals of the talking battery through intervening retardation coils. This results in a varying potential in this part of the circuit which may be impressed on the line to station Y in the following manner:—Transmitter 13, wire m⁶, contacts of key 17', wire m⁵, contacts of other key 17', wire m⁴, through contacts of operated key 17, wire n¹, line n², wire n³, line n⁴, contact of key 17', wire n⁵, contact of the other key 17', wire n⁶, transmitter 13, receiver 14, wire n⁷, contact of key 17', wire n⁸, contact of the other key 17', wire n⁹, switch hook 12, wire l⁸, line wire l⁷, wire l⁶, contact of key 17, wire l⁵, wire l⁴, contact of key 20, wire n¹⁰, wire n¹¹, switch hook 12, wire m⁹, contact of key 17', wire m⁸, contact of other key 17', wire m⁷, back to receiver 14. The current for the conversation from Y to X is supplied to the transmitter and receiver at station Y in exactly the same manner as already described for station X. The actual telephonic circuit just referred to is of course equally effective in both directions.

It will next be necessary to consider the circuits when one master station calls another. This calling of one master station by another may take place in either of two ways. If the second master station is only a short distance away the ringing may be accomplished by the calling station displacing the talking key. For example, if station A' calls station A², this may be done by displacing talking key 1. A ringing cir-

- cuit is established as follows:—Battery 10, wire o^1 , receiver 8, wire o^2 , contact of key 1, wire o^3 , contact of key 1 at station A^2 , wire o^4 , signal 4, wire o^5 , wire o^6 , wire l^1 , wire o^7 , wire o^8 , back to battery 10. It will be observed that this circuit includes the signal at the called station. It however includes some resistance and has a lower voltage than is desirable for calls to remote stations. An alternative calling circuit is as follows:—Battery 11, wire v^3 , wire p^1 , ringing key 6, wire o^3 , contacts of key 1 at station A^2 , wire o^4 , signal 4, wire o^5 , wire o^6 , wire l^1 , wire o^7 , wire o^8 , back to battery 11.
- The called station responds by displacing the indicated key and talking circuits are established as follows:—Battery 10 at station A^1 , wire o^1 , receiver 8, contact of switch hook, wire o^2 , contact of key 1 of station A^1 , wire o^3 , contact of key 1 at station A^2 , wire p^1 , transmitter 7, wire p^2 , contact of key 1, wire p^3 , wire o^5 , wire o^6 , wire l^1 , wire o^7 , wire o^8 , back to battery 10. This circuit includes the receiver of station A^1 , and the transmitter at station A^2 , and is effective for conversation in one direction. For conversation in the opposite direction the circuit is as follows:—Battery 10 at station A^2 , wire q^1 , wire q^2 , receiver 8, contact of switch hook, wire q^3 , contact of key 1, wire q^4 , contact of key 1 at station A^1 , wire q^5 , transmitter 7, wire q^6 , contact of key 1, wire q^7 , wire o^7 , wire l^1 , wire o^8 , back to battery 10. This circuit includes the transmitter at station A^1 , the receiver at station A^2 , and provides for conversation from A^1 to A^2 . It will be observed that the talking circuits from master station to master station are dictograph circuits.
- It will next be necessary to consider the conditions when a master station calls a sub-station. Assuming that master station A^1 calls sub-station X, the calling circuit is as follows:—Battery 10, wire o^1 , receiver 8, switch hook, wire o^2 , wire r^1 , contact of operated key 2, wire r^2 , contact of key 17', lamp 18, wire r^3 , relay 21, wire r^4 , wire r^5 , negative side of battery R^2 , through the battery to wire l^1 , wire o^7 , wire o^8 , battery 10. This circuit provides for the illustration of the electric lamp or other type of visual signal 18, and the operation of the relay, but without imposing an undue potential on the transmitter and receiver of the talking circuit when the latter circuit is completed. An audible signal is provided as follows:—The relay 21 closes a circuit as follows:—Contacts s^1 , wire l^2 , wire l^1 , through battery R^1 , wire l^{10} , wire s^2 , bell 16, switch hook 12, wire s^3 , back to the contact s^1 of relay 21. The sub-station, now being called, answers by removing the receiver from the hook and displacing the indicated key. Conversation takes place as follows:—Battery 10, wire o^1 , receiver 8, switch hook, wire o^2 , wire r^1 , wire s^3 , contact of key 2, wire r^2 , contact of key 17', wire m^5 , contact of the other key 17', wire m^6 , transmitter 13, wire t^1 , wire t^2 , contact of key 17', wire t^3 , wire l^2 , wire o^7 , wire o^8 , back to battery 10. This circuit includes the receiver at master station A^1 and the transmitter at the sub-station providing conversation in one direction. Conversation in the opposite direction takes place through the following circuit:—Battery 10, wire o^1 , wire u^1 , contact of key 1, wire q^8 , transmitter 7, wire q^5 , contact of key 2, wire u^2 , contact of key 17', wire m^8 , contact of other key 17', wire m^7 , receiver 14, wire t^1 , wire t^2 , contact of key 17', wire t^3 , wire l^2 , wire o^7 , wire o^8 , back to battery 10.
- When a sub-station calls a master station the circuit is as follows:—Battery 11, wire v^3 , wire o^7 , wire l^2 , wire t^3 , contact of key 17', wire t^2 , wire t^1 , receiver 14, wire m^7 , contact of key 17', wire m^8 , contact of other key 17', wire u^2 , contact of key 2 at master station A^1 , wire v^1 , signal 4, wire v^2 , wire v^3 , back to battery 11. This circuit effects the selective operation of the signal at the called master station which signal responds by displacing the selected key. The conversation takes place through a circuit already traced in connection with the calling of a sub-station by a master-station. This provides for all conditions of practice, except the conditions when a called line is busy. Assuming that the master station calls a busy sub-station, the circuits are as follows:—Battery 10, wire o^1 , receiver 8, wire o^2 , wire r^1 , contact of key 2, wire r^2 , contact of key 17', signal lamp 18, wire r^3 , relay 21, wire r^4 , wire r^5 , battery R^2 , wire l^1 , wire o^7 , wire o^8 , back to battery 10. This circuit therefore notifies the busy sub-station of the call by the illumination of the signal lamp. The sub-station is thereby notified, as is desirable, but the disturbance of the buzzer or the audible signal is avoided, because the circuit through the audible signal can be completed only when the receiver is on the hook. Finally, the conditions may be considered when a sub-station calls a busy master station. Inasmuch as the busy master station will of course be connected by another key and line than that of the new calling station, it follows that key and signal conditions are presented similar to those already traced when a sub-station calls a master station. The master's visual signal is therefore operated, but the master is provided with a switch 25 by which he may cut off his audible signal at any time if this is desirable.
- In Fig. 2 substantially the same circuits are illustrated as already shown and described in connection with Fig. 1, except that in place of the signal lamps 18 and relay 21, an audible signal 26 is used. This of course limits the number of master sta-

tions somewhat as a code ring will have to be adopted in order that the sub-station may know which master station calls.

It will be observed from the foregoing description that while the sub-stations are joined by an intercommunicating system having the simplicity and directness which characterizes such a system, that on the other hand the master stations may have sensitive transmitters and loud speaking receivers, with circuits kept separate and distinct, as is required with what is known as a "dictograph" system. The general requirements of a dictograph system are pointed out in United States Letters Patent Nos. 844,635, 875,081, 843,186 and 927,230. It is sufficient to mention for the purpose of the present case, that the conversation at the master station should not be returned at the loud speaking receiver of the same station, and furthermore the feature of secrecy, where a master station is involved, should be preserved. The minimum of attention should be required on the part of the master station operator to rules and details of usage. These conditions should be present, not only when one master station is talking to another, but also when any master station is talking to a sub-station. In view of the fact that each master station has its own battery while only a common battery is provided for the sub-stations, and also in view of the foregoing requirements, the dictograph circuits are of somewhat different character when a master station is talking to a sub-station from that when two master stations are talking to one another. When two master stations are talking to one another it will be observed that two batteries supply current for the communication, the same being in the legs of the three wire circuit including the receivers of the respective master stations where the batteries are located. On the other hand, when a master station is talking to a sub-station only one battery furnishes current for the connection, the same being in the third wire of the three wire connection, the other wires respectively containing the telephonic instruments of both stations. In the last mentioned case this third wire is tapped into the circuit of the sub-station at a point between the transmitter and receiver thereof. When, however, the sub-stations are talking with one another this tap is idle, the circuits thereof being opened at the keys 17'. The minimum of trouble of operation is provided for the master stations which is obviously a desirable feature. A master station calls a sub-station by the displacement of a talking key, and this calling circuit is automatically terminated when the sub-station answers. Furthermore, the master station is not called upon to closely bear in mind the returning of the talking key to

normal position, because whenever this is not done, the sub-station is again continuously called. Being called, the sub-station will of course answer, and the answer will be audibly heard at the master station, thereby automatically reminding the master station to return the displaced key to normal position. In this way the system is automatically kept in normal condition without the necessity of imposing any rules or discipline on the master stations.

While the invention has been particularly described with keys at the master stations, and keys have been referred to in certain of the appended claims, this is merely for the purposes of clear and convenient designation, for it is obvious that the same results can be secured by the use of jacks instead of keys, the jacks serving the same functions as the keys in controlling a plurality of circuits by the single actuation of a prescribed part.

It will further be obvious that other adaptations are readily possible, within the skill of an ordinary telephone mechanic, and falling within the spirit and scope of the invention.

What is claimed is:—

1. In a telephone system having a plurality of master stations and a plurality of sub-stations, three wire circuits extending from said master stations to the sub-stations and also to the other master stations, means for including the transmitter and receiver in a master station directly in two wires of any of said three wire connections, and a battery in the third wire thereof when talking to any sub-station, and means for changing said circuits to put the battery in a circuit wire including one of said telephone instruments, when talking to another master station.

2. In a telephone system having a plurality of master stations and a plurality of sub-stations, a pair of telephone instruments and a battery at each master station, means for connecting said battery and telephone instruments respectively into three wires extending from the master station, and means for changing the connections to include the battery in the same wire with one of the pair of instruments when conversation is had to another master station, the third wire continuing to connect points between the transmitter and the receiver at the respective master stations.

3. In a telephone system, a plurality of sub-stations, a master station, and connecting lines between the sub-stations, a three wire circuit extending from the master station to the sub-stations, and means for simultaneously connecting the two wires of said three wire circuit to the sub-station instruments, the third wire being tapped into circuit between the instruments, and eliminating all

calling circuits between the talking keys of the master stations and talking circuits between the talking keys of the several stations, said talking circuits and calling circuits from a master station being closed simultaneously, each of the talking circuits from a sub-station being controlled by each of the talking keys at that station corresponding to a master station.

10 15. In an intercommunicating telephone system, a plurality of sub-stations and a plurality of master stations, a plurality of talking keys at each station, one for each station of the system, a separate calling key at each 15 sub-station, calling circuits between the talking and calling keys of a sub-station and the talking keys of the master stations, other

calling circuits between the talking keys of the master stations and talking circuits between the talking keys of the several stations, said talking circuits and calling circuits from a master station being closed simultaneously, each of the talking circuits from a sub-station other than those leading to a master station being opened upon the actuation of the talking key at the sub-station corresponding to said master station.

Signed at Jamaica, in the county of Queens and State of New York, this 8th day of October, A. D. 1918.

WALLACE PFAU ANDRICK.

- other connections from said instruments at such sub-station.
4. In a telephone system, a plurality of sub-stations, a master station, having a battery, and connecting lines between the sub-stations, a three wire circuit extending from the master station to the sub-stations, and means for simultaneously connecting two wires of said three wire circuit to the sub-station instruments, the third wire being tapped into circuit between the instruments, and including said battery, and eliminating all other connections from said instruments at such sub-station.
5. In a telephone system, a plurality of master stations, a plurality of sub-stations, a source of current for the master stations, a three wire circuit extending therefrom to each of the sub-stations, a connecting system having a common battery joining the various sub-stations, and means for simultaneously connecting the instruments of any sub-station with the three wires to a master station, and eliminating all other connections to the other sub-stations, and to the common battery.
6. In a telephone system, a master station, a plurality of sub-stations each having visual signals and an audible signal, means for calling said sub-stations from the master station, and means operating both audible and visual signals at the sub-station when the said sub-station is not in use, and said visual signal exclusively when the station is busy.
7. In a telephone system, a master station, a plurality of sub-stations, visual and audible signals at both the master station and sub-stations, means for operating the visual signals at the respective stations under all conditions, and means for preventing the operation of the audible signals at the respective stations when the latter are busy.
8. In a telephone system, a plurality of sub-stations, a master station, three wire circuits joining the master station with the said sub-stations, an inter-communicating system joining the said sub-stations together, means operated by the single displacement of a talking key at the master station for calling a sub-station, and means for terminating said calling circuit when the said sub-station answers.
9. In a telephone system, a master station, a plurality of sub-stations, a loud speaking receiver and sensitive transmitter at the master station, and means for calling the sub-station by the single displacement of a talking key at the master station controlled by the removal of the receiver from the switch hook of a substation, whereby the accidental failure to return the talking key to normal position at the master station will again call the sub-station when the receiver is again placed upon its hook.
10. In an intercommunicating telephone system, a plurality of sub-stations, a plurality of master stations, means for connecting the transmitters and receivers of two sub-stations in a talking circuit, and separate means for connecting the receiver of a master station in a talking circuit with a transmitter of a sub-station or another master station and establishing a similar connection between the transmitter of a master station and the receiver of a sub-station or another master station.
11. In an intercommunicating telephone system, a plurality of sub-stations, a plurality of master stations, means for connecting the transmitters and receivers of two sub-stations in a talking circuit, separate means for connecting the receiver of a master station in a talking circuit with a transmitter of a sub-station or another master station and establishing a similar connection between the transmitter of a master station and the receiver of a sub-station or another master station, and means for always giving a visual indication at a station of a call from another station if one of the two stations is a master station.
12. In an intercommunicating telephone system, a plurality of sub-stations, a plurality of master stations, means for connecting the transmitters and receivers of two sub-stations in a talking circuit, separate means for connecting the receiver of a master station in a talking circuit with a transmitter of a sub-station or another master station and establishing a similar connection between the transmitter of a master station and the receiver of a sub-station or another master station, and means for always giving a visual indication at a station of a call from another station if one of the two stations is a master station and for giving an audible signal if the station called is not busy.
13. In an intercommunicating telephone system, a plurality of sub-stations and a plurality of master stations, a plurality of talking keys at each station, one for each station of the system, a separate calling key at each sub-station, calling circuits between the talking and calling keys of a sub-station and the talking keys of the master stations other calling circuits between the talking keys of the master stations and talking circuits between the talking keys of the several stations, said talking circuits and calling circuits from a master station being closed simultaneously.
14. In an intercommunicating telephone system, a plurality of sub-stations and a plurality of master stations, a plurality of talking keys at each station, one for each station of the system, a separate calling key at each sub-station, calling circuits between the talking and calling keys of a sub-station and the talking keys of the master stations, other
